United States Patent Office

Des. 230,111
Patented Jan. 29, 1974

230,111

SOFA

Stapleton Long, Morristown, Tenn., assignor to The Berkline Corporation, West Springfield, Mass.

Filed Aug. 30, 1972, Ser. No. 284,933

Term of patent 3½ years

Int. Cl. D6—01

U.S. Cl. D6—63

FIG. 1.

FIG. 2.

FIG. 1 is a view, in front elevation, of a sofa showing my design; and

FIG. 2 is a view, in side perspective, of the sofa of FIG. 1.

The sofa back is plain and conventional throughout and the side not shown is identical to that shown.

I claim:

The ornamental design for a sofa, as shown and described.
